UNITED STATES PATENT OFFICE.

MENDAL A. WITOFSKY, OF BUTTE, MONTANA.

TRUNK-LOCKING DEVICE.

Application filed March 12, 1924. Serial No. 698,652.

To all whom it may concern:

Be it known that I, MENDAL A. WITOFSKY, a citizen of the United States, residing at Butte, in the county of Silver Bow and State 5 of Montana, have invented certain new and useful Improvements in Trunk-Locking Devices, of which the following is a specification.

This invention relates to trunk fastening devices and has special reference to means for holding the members of a wardrobe trunk in closed position. The primary object of the invention is to provide a device of simple construction which may be applied 10 to the inside of the trunk so as to be entirely concealed when the trunk is closed, and which will be automatically operated by the raising or lowering of the trunk top. Another object of the invention is to provide a 15 fastening device which will serve as a stay to support the trunk top or lid in raised position and which will permit the two side members of the trunk to be readily swung to open or closed position. Other objects of 20 the invention will appear incidentally in the course of the following description, and the invention resides in certain novel features which will be particularly pointed out in the appended claims.

30 The invention is illustrated in the accompanying drawing, in which—

Figure 1 is a perspective view of my improved fastening device, a wardrobe trunk being illustrated in skeleton in order that 35 the position of the working parts may be readily comprehended;

Fig. 2 is a vertical section taken longitudinally of the trunk showing the improved fastening device in side elevation with the 40 lid or cover of the trunk raised, and

Fig. 3 is an enlarged detail perspective view showing the hook and eye members of the fastenings separated but approximately in their relative working positions.

45 The trunk consists of a side or body member 1 which is adapted to set on end and is relatively stationary, a similar side member 2 hinged at one side edge to the relatively stationary member 1 and terminating short 50 of the upper end or top of said member, and a top or lid member 3 which is hinged to the outer side of the member 2 at the upper end of the same and is adapted to fold over onto the swinging side member 2 against the upper 55 end of the relatively stationary member 1, as will be readily understood upon refer-

ence to the drawing. All these parts are commonly found in wardrobe trunks and, in themselves, constitute no part of my present invention.

In carrying out my invention, I secure to the trunk member 1 adjacent that side edge which is remote from the hinges connecting the members 1 and 2, eyes 4 having base plates 5 through which fastening devices are inserted to secure the eyes to the trunk member. Upon the inner side of the member 2 adjacent the meeting edge thereof, I provide loops or guides 6 in which is slidably mounted a latch bar 7 carrying hooks 8 which project laterally beyond the edge of the trunk member 2 and have upturned bills 9 which are adapted to engage through the eyes 4 and thereby firmly hold the trunk members 1 and 2 together in closed position. Adjacent the upper end of the swinging trunk member 2, I secure a bracket 10 having a pin or stud 11 projecting inwardly therefrom and upon the said pin or stud, I pivotally mount a toggle link 12 which is provided at one end with a longitudinal slot 13 engaging upon a pin or stud 14 projecting laterally from the upper end of the latch bar 7. The opposite end of the link 12 is connected by a pivot 15 with a similar toggle link 16, the latter being pivotally engaged at its opposite end upon a pin or stud 17 projecting from a bracket 18 secured to the inner side of one end portion of the trunk lid or top 3.

When the trunk is fully closed, the top or lid member 3 will be locked to the top or upper end of the trunk body member 1 by a lock 19 of any preferred construction. In the closed position of the trunk, the lid 3 will fit closely upon the upper end of the trunk member 2 and against the upper end of the trunk member 1 and the toggle links 12 and 16 will be out of alinement, as shown in Fig. 1, the link 16 depending into the trunk member 2 and the link 12 being disposed in an oblique position with its slotted end uppermost so that the latch bar 7 will be raised and the hooks 8 closely engaged in the eyes 4. If access to the trunk be desired, the lock 19 is opened through the manipulation of the usual key, and the lid member 3 is then swung upwardly, as shown in Fig. 2. As the lid is raised, the bracket 18 will, of course, be swung upwardly and outwardly and will pull upon the toggle link 16 so that the toggle will be straightened, as shown in

- Fig. 2, and the slotted end of the link 12 will swing downwardly so that the latch bar 7 will be slid toward the bottom of the trunk and the hooks 8 withdrawn from the eyes 4. 5 The trunk members 1 and 2 may then be swung apart in the usual manner, and it will be readily noted upon reference to Fig. 2 that in this position the links 12 and 16 will be in alinement and will serve as a stay or 10 brace to maintain the top 3 in its raised position.

It will be readily noted that I have provided an exceedingly simple device which is entirely concealed within the trunk and requires no attention upon the part of the user of the trunk. The device operates entirely automatically and is controlled solely by the raising or lowering of the trunk lid. All springs and other similar moving parts are 20 eliminated in my device so that the expense of producing and applying the fastening is minimized while the simplicity and compact arrangement of the working parts overcomes normal liability of the parts to get out of 25 order. The device may be applied at a slight expense to trunks now in use and will not interfere with any of the adjuncts of the trunks nor lessen the capacity of the same in any way.

Having thus described the invention, I claim:

1. The combination with a wardrobe trunk comprising a relatively stationary member, a mating member hinged to the stationary member and a lid hinged upon the upper end of the relatively moving member to

swing outwardly relative thereto, of eyes secured upon the inner side of the relatively stationary trunk member adjacent the edge thereof, a latch bar slidably mounted upon the relatively movable trunk member, hooks carried by the latch bar and disposed below the eyes, and operative link connections between the trunk lid and the latch bar whereby closing of the lid will lift the hooks into engagement with the eyes and raising of the lid will lower the hooks from the eyes, the link connections holding the lid in open position.

2. The combination with a wardrobe trunk comprising two body members connected together for relative swinging movement and a lid hinged to the upper end of one of said members and adapted to abut the open side of the other of said members, a fastening device including a latch bar slidably mounted upon that trunk member which is closed by the lid, hooks carried by the latch bar, and means on the mating trunk member to be engaged by said hooks, a toggle link pivotally mounted between its ends upon the inner side of the trunk member to which the lid is attached, said link being operatively connected at its inner end with the upper end of the latch bar, and a second toggle link pivoted at its inner end to the outer end of the first-mentioned toggle link and having its outer end pivotally attached to the trunk lid at the hinged side thereof.

In testimony whereof I affix my signature.

MENDAL A. WITOFSKY.
